UNITED STATES PATENT OFFICE.

FRITZ GIRARD, OF HANAU-ON-THE-MAIN, GERMANY, ASSIGNOR TO THE FIRM, QUARZ-LAMPEN-GESELLSCHAFT MIT BESCHRÄNKTER HAFTUNG, OF HANAU-ON-THE-MAIN, GERMANY.

ELECTRIC HEAT RADIATOR.

Application filed June 10, 1922. Serial No. 567,367.

To all whom it may concern:

Be it known that I, FRITZ GIRARD, a citizen of Germany, residing at Hanau-on-the-Main, Germany, have invented certain new and useful Improvements in Electric Heat Radiators, of which the following is a specification.

My invention has reference to electric heat radiating and transmitting devices, and it is particularly intended to provide novel means for the easy regulation and control of devices of this kind and in general to so improve and perfect the construction and arrangement of the kinds of apparatus of the class referred to that they may be safely applied to the skin or utilized for other purposes, where facility of regulation of the heat, or easy applicability to a delicate object is of importance.

For the purpose of partial heating of rooms electrical heating devices are in use in which the heating body is arranged in the focus of a parabolic mirror; and by this means parallel heat rays are produced similar to the operation of optical reflectors. Heat radiation of this kind may also be employed for therapeutic purposes. These kinds of apparatus of otherwise simple construction are open to the difficulty that there is no way of limiting or of controlling the heat radiation, as is frequently required for therapeutic purposes, and that the intensity of the radiation of heat could only be regulated heretofore by including a special kind of controlling or regulating means in advance of the radiator, such as for instance a variable electric resistance.

My invention is intended to effect this regulation and control in a novel and efficient manner, particularly by the provision of means associated with the reflector or mechanical parts of the heat radiating device. The invention is shown as embodied by way of example in a heat radiator provided with the usual reflector in

Figure 1 in side view with parts in section.

Figure 2 is an elevation of a portion of the outer end of the reflector in one of various preferred forms of construction.

Figures 3 and 4 illustrate respectively and in a diagrammatic manner two different forms of reflector as an illustration of one of the important elements of my invention.

Figures 3' and 4' are diagrams illustrating

in a conventional manner the temperature curves obtained respectively with the reflector indicated in Figures 3 and 4 respectively.

The parabolic mirror or reflector *a* (Figure 1) is provided with a substantially conical extension *b*, the interior of which, in order to assist and increase the heat reflecting action, is provided with special heat reflecting instrumentalities. Among other means I may make use in the example shown in the drawing of a coating of silver, nickel, or of aluminium or the like upon the inner walls of the conical extension, the said coating being preferably highly polished, so as to adapt the device for the substantially axial radiation of the rays of heat emanating from the source of heat mounted at *k* for instance. Furthermore, the reflecting interior surface, if the conical curvature is properly adjusted, causes a deflection of all parallel rays which are not directly made to enter the end opening of the extension, so as to direct them towards said aperture. Thus the funnel shaped extension, as in the case of rays of light, causes a concentration of the heat rays over the entire surface of the escape opening. The path of the rays emitted by the heating body *k* will be apparent from the drawing, while the action of the heat is clearly shown in the diagrams of Figures 3, 3' and 4, 4' respectively.

The crowding together of the heat rays corresponds to a change of temperature at the funnel opening. With the length of the funnel the escape opening is reduced, and the more are the rays of heat proportionally concentrated at the opening. Figures 3' and 4' represent the temperatures obtained in the different cases. In order to effect a regulation and control of the quantity of heat radiated per unit of irradiated surface at the funnel opening, and in order to increase that ratio, the funnel *b* may be connected with a second and third funnel *c* and *d* respectively, possessing the same degree of conical curvature as clearly shown in Figure 1 of the drawing.

Diaphragms are provided for reducing the area of the opening of the funnel. A form of diaphragm which I may employ for example in connection with my invention is shown in Figure 2 of the drawing. These diaphragms *e* are mounted at the end of

the funnel, so as to be easily detachable. The free opening of the diaphragm is surrounded by a heat insulating annulus or ring *f* of a non-conductor of heat, of cork or of a cork-composition for instance, which prevents convection of heat towards the protecting disc *g*. The said protecting disc *g* may itself be provided with a similar annulus *h* made from a bad conductor of heat, which prevents burning of the skin, when the opening portion of the diaphragm is brought in contact with the living body. An additional regulation of heat may be effected by mounting a regulatable balance resistance coil in the supporting pillar of the reflecting device, such resistance being provided with a semi-circular contact slide adapted to cut in and out the required amount of resistance.

Among the various advantages according to the novel arrangement I may mention the almost complete utilization of the radiated heat which corresponds to a very great reduction of the amount of watts required as compared with the kinds of apparatus heretofore employed, and the possibility of producing a great variation of the heat applied to the living body in a very simple manner, by the use of funnel extensions of different length, as well as by the use of diaphragms and by the possibility of a very convenient manner of regulating the current.

While I have herein described my invention in its broad aspects, I wish it to be understood that it is obviously not restricted to the particular kinds of embodiments as shown and described, but changes and alterations in the structure and combination of parts may occur to adapt the device to varying conditions of use, and without deviating from the spirit of the invention as expressed in the claims.

I claim:

1. Heat radiator comprising in combination, a substantially frusto-conical reflector, a parabolic reflector covering the larger opening of said frusto-conical reflector and a source of heat in the focus of said parabolic reflector.

2. Heat radiator comprising in combination, a plurality of frusto-conical reflectors disengageably assembled, the larger opening

of one adjoining the smaller opening of another reflector, a parabolic reflector covering the larger opening of the largest frusto-conical reflector and a source of heat in the focus of said parabolic reflector.

3. Heat radiator comprising in combination, a parabolic reflector, a source of heat in the focus of said reflector, an open-ended frusto-conical reflector associated with said parabolic reflector in such manner that the totality of the heat rays emitted by said source, including those reflected by said parabolic reflector, is evenly distributed over the smaller opening of said frusto-conical reflector, and a diaphragm for reducing the cross-sectional area of the bundle of heat rays removably attached to said smaller opening.

4. Heat radiator comprising in combination, a parabolic reflector, a source of heat in the focus of said reflector, an open-ended frusto-conical reflector associated with said parabolic reflector in such manner that the totality of the heat rays emitted by said source, including those reflected by said parabolic reflector, is evenly distributed over the smaller opening of said frusto-conical reflector, a diaphragm for reducing the cross-sectional area of the bundle of heat rays removably attached to said smaller opening, and means associated with said diaphragm for preventing contact between it and the body exposed to the action of the heat rays.

5. Heat reflector comprising in combination, a parabolic reflector, a source of heat in the focus of said reflector, and open-ended frusto-conical reflector associated with said parabolic reflector in such manner that the totality of the heat rays emitted by said source, including those reflected by said parabolic reflector, is evenly distributed over the smaller opening of said frusto-conical reflector, a diaphragm for reducing the cross-sectional area of the bundle of heat rays removably attached to said smaller opening, a perforated protective disc in front of said diaphragm, and a heat insulating ring connecting said disc and said diaphragm.

In testimony whereof I affix my signature.

FRITZ GIRARD.
